Primary Examiner — Ricky Pham

(57) **CLAIM**

We claim the ornamental design for a dinnerware utensil, as shown and described.

DESCRIPTION

FIG. 1 is a front perspective view of a first embodiment of our new design for a dinnerware utensil, featuring the top, front and right sides thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top elevational view thereof;

FIG. 7 is a bottom elevational view thereof;

FIG. 8 is a front perspective view of a second embodiment of our new design for a dinnerware utensil, featuring the top, front and right sides thereof;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top elevational view thereof;

FIG. 14 is a bottom elevational view thereof;

FIG. 15 is a front perspective view of a third embodiment of our new design for a dinnerware utensil, featuring the top, front sides and right sides thereof;

FIG. 16 is a front elevational view thereof;

FIG. 17 is a rear elevational view thereof;

FIG. 18 is a left side elevational view thereof;

FIG. 19 is a right side elevational view thereof;

FIG. 20 is a top elevational view thereof;

FIG. 21 is a bottom elevational view thereof;

FIG. 22 is a front perspective view of a fourth embodiment of our new design for a dinnerware utensil, featuring the top, front and right sides thereof;

FIG. 23 is a front elevational view thereof;

FIG. 24 is a rear elevational view thereof;

FIG. 25 is a left side elevational view thereof;

FIG. 26 is a right side elevational view thereof;

FIG. 27 is a top elevational view thereof; and,

FIG. 28 is a bottom elevational view thereof.
